SELECTIVE DEMETHYLATION OF TRI-METHYLPENTANES TO FORM TRIPTANE

Vladimir Haensel and Vladimir N. Ipatieff, Riverside, Ill., assignors to Universal Oil Products Company, Chicago, Ill., a corporation of Delaware

Application September 30, 1943, Serial No. 504,456

3 Claims. (Cl. 260—683.6)

1

This invention relates to the conversion of hydrocarbons and more particularly to the conversion of an aliphatic hydrocarbon containing at least six carbon atoms to the molecule into an aliphatic hydrocarbon having at least one carbon atom less to the molecule.

We have shown that aliphatic hydrocarbons, and preferably paraffinic hydrocarbons having a branched chain structure, may be subjected to selective demethylation in the presence of hydrogen and a hydrogenating catalyst at a temperature of from about 350° to about 700° F. and preferably of from about 400° to about 650° F. under a pressure of substantially atmospheric to 1500 pounds per square inch, or more. Suitable catalysts comprise the metals of the iron group and their oxides including iron, nickel and cobalt, and the noble metals, platinum and palladium, used as such or supported by carriers. Under some conditions of operation, selective demethylation may also be effected in the presence of an oxide or sulfide of chromium, molybdenum, tungsten and vanadium. A highly selective catalyst contains approximately 66 per cent by weight of total nickel, 30 per cent of diatomaceous earth and 4 per cent of oxygen, the latter being present with nickel as nickel oxide.

The present invention is characterized by one or more of the following features, either singly or in combination.

(1) Selective demethylation of a branched chain aliphatic hydrocarbon in the manner hereinafore set forth, separating a fraction containing methane from the products of said demethylation, subjecting said methane fraction to conversion into hydrogen, and supplying the resultant hydrogen to the demethylation process.

(2) Purifying the hydrogen being supplied to the demethylation process to remove any moisture which may be present therein. The presence of moisture has been found to be detrimental to the catalyst employed in the demethylation process and its substantial removal is essential for efficient operation of the demethylation process.

(3) Close control of the temperature in the reaction zone of the selective demethylation process since experiments have shown that the temperature employed is critical and, in accordance with the present invention, the control of temperature is effected by means of a circulating heat exchange medium.

(4) Maintaining a temperature differential between the inlet and outlet of the demethylation reactor.

2

(5) Close fractionation of the charging stock to the process to separate a selected fraction for treatment in the selective demethylation process in order to obtain improved results therein.

(6) Close fractionation of the products from the demethylation process, with recycle of particular fractions in order to obtain increased yields of the desired product.

(7) Separation of a hydrogen-containing fraction and a methane-containing fraction from the demethylation products by flashing in a plurality of zones maintained at successively decreased pressures.

The present invention is applicable to the treatment of aliphatic hydrocarbons and particularly branched chain paraffinic hydrocarbons containing at least six carbon atoms per molecule. It is also applicable to the treatment of naphthenic hydrocarbons containing alkyl side chains, although the results obtained are not necessarily equivalent. The invention is particularly applicable to the production of triptane which is otherwise known as 2,2,3-trimethylbutane.

In a broad aspect the present invention relates to a process for converting an aliphatic hydrocarbon into an aliphatic hydrocarbon containing at least one carbon atom less to the molecule, which comprises subjecting the first mentioned aliphatic hydrocarbon to selective demethylation in the presence of hydrogen and a hydrogenating catalyst under conditions to produce an aliphatic hydrocarbon having at least one carbon atom less to the molecule, separating from the demethylation products a methane-containing fraction, subjecting the latter fraction to conversion to produce hydrogen therefrom, and supplying at least a portion of the resultant hydrogen to the demethylation reaction.

In one specific embodiment the present invention relates to a process for producing triptane which comprises heating a fraction containing 2,2,3-trimethylpentane, simultaneously heating a hydrogen fraction substantially free of moisture, commingling the heated streams and introducing the same at a temperature of from about 400° to about 650° F. into a reaction zone, maintaining the temperature in the reaction zone within a relatively narrow range by means of indirect contact with a circulating heat exchange medium, flashing the demethylation products to separate a hydrogen-containing fraction, further flashing the remaining products to separate a methane-containing fraction, subjecting the methane-containing fraction to reaction with water in the presence of a catalyst to produce hydrogen, heat-

ing said hydrogen and commingling the same with said fraction containing 2,2,3-trimethylpentane as aforesaid.

The invention will be further explained in connection with the attached diagrammatic flow drawing comprising Figures 1 and 1A which illustrate several specific embodiments of the invention. In the interest of simplicity, the description of the drawing will be limited to a process for the treatment of an isooctane fraction for the production of triptane. It is understood, however, that the broad scope of the invention is not so limited, but that it is applicable, with suitable modifications, to the treatment of other hydrocarbons. In general, the preferred charging stocks are those containing at least five carbon atoms to the molecule and having a quaternary carbon atom, and particularly those having a triptyl group. By quaternary carbon atom it is meant a carbon atom which is combined chemically with four other carbon atoms, neopentane being the simplest example of a hydrocarbon containing a quaternary carbon atom. By triptyl group it is meant a hydrocarbon containing adjacent quaternary and tertiary carbon atoms; that is, one carbon atom is combined chemically with four other carbon atoms and one of said four carbon atoms is tertiary in that it is bound to the quaternary carbon atom, to two other carbon atoms and to only one hydrogen atom.

The charging stock to the process of the present invention may suitably comprise an isooctane fraction produced by the polymerization of normal and isobutylenes in the presence of suitable catalysts and particularly sulfuric acid, the latter polymerization being effected at a temperature within the range of from about 150° to about 200° F., followed by hydrogenation of the polymerization products. The hydrogenated products may be subjected to fractionation or other treatment to separate an isooctane fraction having an initial boiling point of about 194° F. and containing 2,2,4-, 2,2,3-, 2,3,4-, and 2,3,3-trimethylpentanes along with higher boiling compounds.

The isooctane fraction charging stock, at a suitable temperature and pressure, is introduced to the process through line 1 containing valve 2 and is directed into fractionator 3. Fractionator 3 may comprise any suitable zone for effecting the separation of the products introduced thereto into the desired fractions and may suitably comprise a fractionating column containing bubble trays, baffle plates, side-to-side pans or other contact means. Fractionator 3 is preferably heated at the bottom by means of closed coil 4 or other suitable means and is cooled at the top in any suitable manner such as by recycling a portion of the condensed overhead fraction as will be hereinafter described.

As applied to the particular isooctane fraction as heretofore set forth, zone 3 will be operated to separate an overhead fraction having an initial boiling point of about 194° F. and an end boiling point of about 239° F. from higher boiling bottoms fraction. The higher boiling bottoms fraction is withdrawn from the lower portion of zone 3 through line 5 containing valve 6 to storage or elsewhere as desired. The overhead fraction, which now comprises a mixture of the various trimethylpentanes, is withdrawn from the upper portion of zone 3 through line 7 containing valve 8 and is passed through condenser 9 and rundown line 10 containing valve 11 into receiver 12, having conventional gas release line 13 containing valve 14. The condensate in receiver 12 is

withdrawn therefrom through line 15 containing valve 16 to pump 17, by means of which a regulated portion thereof is recycled by way of line 18 containing valve 19 to the upper portion of fractionator 3 to serve as a cooling and refluxing medium therein, while the remaining portion of the condensate from receiver 12 is directed through line 20, valve 21, heat exchanger or other suitable heating means 21' to fractionator 22.

Fractionator 22 may be similar to heretofore described fractionator 3 and contains closed coil 23 or other suitable heating means in the lower portion thereof. This fractionator will function to separate an overhead fraction comprising hydrocarbons boiling below about 226° F. from higher boiling trimethylpentanes. The light fraction withdrawn as an overhead product from fractionator 22 will comprise principally 2,2,4-trimethylpentane and 2,3-dimethylpentane, the latter being produced in the process as will be hereinafter set forth. This fraction is directed through line 24 containing valve 25 into and through condenser 26, rundown line 27 and valve 28 into receiver 29, having conventional gas release line 30 containing valve 31. The condensate in receiver 29 may be withdrawn therefrom through line 32 and valve 33 to pump 34, by means of which a regulated portion thereof may be recycled by way of line 35 and valve 36 to the upper portion of fractionator 22 to serve as a cooling and refluxing medium therein, while the remaining portion of the condensate from receiver 29 may be withdrawn from the process through line 37 and valve 38 to storage or elsewhere as desired.

The bottoms product in fractionator 22 will comprise principally 2,2,3-, 2,3,4-, and 2,3,3-trimethylpentanes and may be withdrawn therefrom through line 39 and valve 40 to pump 41 by means of which it may be supplied to furnace 42 having heating coil 43 disposed therein. In passing through coil 43, the hydrocarbons are heated to the desired temperature which, as heretofore set forth, will be within the range of 350° to 700° F. and preferably within the range of 400° to 650° F., at a superatmospheric pressure which will be correlated with the temperature in order to obtain the desired demethylation. It has been found that when higher pressures are employed, generally higher operating temperatures are required. In one specific operation of the present process, the hydrocarbons are heated in coil 43 to a temperature of about 500° F. at a superatmospheric pressure of about 510 pounds per square inch.

The heated products are withdrawn from coil 43 through line 44 and may be supplied through valve 45 to mixing chamber 46. In chamber 46, hydrocarbons are admixed with separately heated hydrogen, the latter being introduced to the process through line 47 containing valve 48 and supplied to heating coil 49 disposed in furnace 50. The hydrogen is heated to the desired temperature and then supplied through line 51 and valve 52 into mixing chamber 46. Mixing chamber 46 may comprise any suitable apparatus and may or may not contain a bed of packing. The function of the mixing chamber is to obtain intimate mixing of the hydrocarbons and hydrogen and also to separate out any unvaporized material. The unvaporized material may comprise, for example, lubricating oil fractions which are carried over with the hydrogen from the compressors. The unvaporized material may be withdrawn from chamber 46 through line 53 containing valve 54. It is understood, when desired, that the hydro-

gen and hydrocarbons may be heated in admixture in one heating zone and that mixing chamber 46 may be omitted. Even in case separate heaters are provided for the hydrocarbons and hydrogen, mixing chamber 46 may be omitted and the heated hydrocarbons may be directed from line 44 through line 55 containing valve 56, while the heated hydrogen may be directed through line 57 containing valve 58. The heated hydrogen and hydrocarbons may then be directed, either through line 59 and valve 60 from mixing chamber 46 or through by-pass lines 55 and 57, into reactor 61, which may comprise any suitable apparatus and which contains a suitable hydrogenating catalyst as heretofore set forth.

One of the important features of the demethylation process is that the temperature within the reaction zone must be maintained within a critical narrow range. When the temperature in this zone becomes too high, there is excessive demethylation of the hydrocarbons and, on the other hand, if the temperature is too low, selective demethylation does not occur to any substantial extent. As heretofore set forth, the exact temperature will depend upon the pressure. One particularly suitable method of maintaining close control of the temperature is by means of a reactor, as illustrated, containing tubes in which the catalyst is disposed, and provision for circulating a heat exchange medium in the annular space surrounding the tubes. Reactor 61 is therefore preferably of this form, although it is understood that other suitable types of reaction zones may be employed.

In order to maintain close control of the reaction temperature, drum 62 may be filled with any suitable heat exchange medium, such as Dowtherm, tetralin or the like, which circulates in a thermo-siphon system through line 63, line 64 and valve 65 into the space surrounding the tubes in reactor 61 and is returned by way of line 66 to drum 62. The vaporous material from drum 62 passes through line 67, valve 68 and line 69 into and through condenser 70 containing suitable cooling means such as closed coil 71. The condensate from the condenser passes through rundown line 72 back into drum 62. Drum 62 and accordingly the space surrounding the catalyst-containing tubes in reactor 61 will be operated at the desired pressure in order to maintain the heat exchange medium in the space surrounding the catalyst-containing tubes as a boiling liquid. This may be any suitable superatmospheric pressure or, in certain cases, may even comprise subatmospheric pressure, depending upon the particular heat exchange medium employed. Vacuum operation may be accomplished by means of vacuum jet 73 having line 74 and valve 75 for the introduction of steam or other suitable gas and outlet line 76, and being in communication with condenser 70 by means of line 69 and valve 71. Even when superatmospheric pressure is employed in drum 62, vacuum jet 73 and its appurtenances may be employed at the start of operation or intermittently during operation, if desired, to remove incondensable gases from the system. These incondensable gases interfere with the pressure on the heat exchange medium and therefore must be vented as required.

The demethylation reaction is highly exothermic and usually will liberate enough heat to maintain the heat exchange medium at the desired temperature. However, in case additional heat is required and also in order to start up the unit, all or a portion of the heat exchange

70
75

medium may be directed from line 63 through line 78 and valve 79 to heating coil 80 disposed in furnace 81, wherein the heat exchange medium is heated to the desired temperature, and the heated material may be directed through line 82 containing valve 83 into the surrounding space in reactor 61. An extension of line 63 containing valve 84 is provided either for the introduction of heat exchange medium to, or the withdrawal of the heat exchange medium from the process.

Since the temperature of the demethylation reaction is so closely related to the pressure, in another embodiment of the invention a temperature differential of from about 10° to about 20° F. may be maintained between the inlet and outlet sections of reactor 61. As the hydrogen is consumed in the lower portion of the reaction zone, there occurs a decrease in available hydrogen and accordingly a reduction in pressure in the upper portion of the reaction zone. One particularly suitable means of accomplishing the temperature differential in reactor 61 is by maintaining a pressure differential between the upper and lower sections of the space surrounding the catalyst-containing tubes, since the temperature of the liquid therein is dependent upon the pressure. This difference in pressure may be obtained by maintaining a level of liquid in drum 62, as illustrated diagrammatically by line 85, and accordingly in the surrounding space in reactor 61, as indicated by line 85', the liquid levels being approximately the same height as the level of catalyst in the tubes of reactor 61. The pressures at the lower portion of the surrounding space and drum will thereby be higher due to the fluid head of the liquids therein.

Although upflow of hydrocarbons and hydrogen is illustrated in reactor 61, it is understood that downflow may be used. The products from reactor 61 may be withdrawn therefrom through line 86 containing valve 87 into and through condenser 88, line 89 and valve 90, and may be supplied to flash zone 91. Line 55' containing valve 56' is provided in order to by-pass the reactor and supply the heated hydrocarbons directly into line 86. This by-pass will be used primarily in case excessive temperatures develop in reactor 61. A sufficient reduction in the temperature in the reaction zone may be accomplished solely by means of by-passing the reactor in this manner. When desired, hydrogen from line 47 or line 96 may be supplied through valve 51' and line 51 and the unheated hydrogen passed through lines 57 and 59 into reactor 61 in order to effect all or a part of the desired cooling.

Flash zone 91 may comprise the first of a series of flash zones being operated at successively decreasing pressures, as illustrated by flash zones 91 and 92. It is understood, however, that one or three or more, and preferably three, of such zones are employed. Assuming that the products being introduced into zone 91 are at a pressure of about 500 pounds, the pressure may be reduced by means of valve 90 to about 200 pounds per square inch. A level of liquid is maintained in zone 91 and, due to the preferential solubility of methane in the hydrocarbon liquid, a light overhead fraction will be released which will be high in hydrogen content. This overhead fraction may then be directed through line 93 and valve 94 to compressor, pump or the like 95, by means of which the hydrogen may be supplied through line 96 and valve 97 into line 47 for treatment in the manner as heretofore set forth.

The unvaporized bottoms from flash zone 91

which will contain substantial proportions of methane, may be withdrawn therefrom through line 98 and reduced in pressure as it passes through valve 99 and introduced into flash zone 92. Assuming that three flash zones are employed, the pressure reduction may be from about 200 pounds in the first flash zone to about 70 pounds in the second flash zone and down to about 25 pounds in the third flash zone. It is understood that the present invention is not limited to these particular pressures and any suitable series of pressure reductions may be employed. A level of unvaporized liquid is likewise preferably maintained in flash zone 92 but, in this case, the liberated overhead fraction will be rich in methane and may be withdrawn from zone 92 through line 100 and valve 101 and then may be passed through line 102, wherefrom a portion may be removed from the process through line 103 but, in accordance with the preferred embodiment of the present invention, at least a portion thereof is directed through line 104 and valve 105 for further treatment in the manner to be herein-after described in detail. In case only one flash zone is employed or for other reasons, all or a portion of the overhead fraction from flash zone 91 may be directed through line 102 and valve 106 for removal from the process or treatment in the manner to be hereinafter described in detail.

Any other suitable means of separating a methane fraction may also be employed within the scope of the present invention and this may comprise, for example:

(1) Absorbing the methane in a liquid stream and subsequently stripping the methane therefrom.

(2) Absorbing the methane on a suitable solid adsorbent, such as activated carbon or the like, and then subsequently stripping the methane therefrom.

It is understood, however, that these various alternative means are not necessarily equivalent in their efficiency in separating the methane from the other products. The unvaporized material in flash zone 92 may be withdrawn from the lower portion thereof through line 107 and valve 108 to pump 109, by means of which it may be directed through line 110 and valve 111 into fractionator 112. Fractionator 112 may be similar to the heretofore described fractionators, having reboiler 113 or other suitable heating means in the lower portion thereof, and will function to separate an overhead fraction having an end boiling point of about 158° F. from higher boiling material. The overhead fraction, which will comprise principally pentane, 2,2 and 2,3-dimethylbutane, may be withdrawn from the upper portion of fractionator 112 through line 114, valve 115, condenser 116, rundown line 117 and valve 118 into receiver 119, having conventional gas release line 121 containing valve 120. The condensate in receiver 119 may be withdrawn therefrom through line 122 and valve 123 to pump 124, by means of which a regulated portion thereof may be recycled by way of line 125 and valve 126 to the upper portion of fractionator 112 to serve as a cooling and refluxing medium therein, while the remaining portion of the condensate from receiver 119 may be withdrawn from the process by way of line 127 and valve 128 to storage or elsewhere as desired.

The bottoms product may be withdrawn from fractionator 112 through line 129 and valve 130 to pump 131 by means of which it may be directed through line 132 and valve 133 to fractionator 134, which may be similar to the heretofore described

fractionators and which may contain heating coil 135 or other suitable heating means in the lower portion thereof. Fractionator 134 will function to separate an overhead fraction having an initial boiling point of about 158° F. and an end boiling point of about 185° F. and comprising principally triptane, from a higher boiling fraction comprising principally unconverted trimethylpentanes and a minor proportion of 2,3-dimethylpentane.

10 The unconverted trimethylpentanes may be withdrawn from the lower portion of fractionator 134 through line 136 and may be withdrawn from the process through line 137 but, in a preferred embodiment of the invention, at least a portion of this stream is directed through line 138 and valve 139 to pump 140 by means of which it is directed through line 141 and valve 142 into line 20 to be supplied into fractionator 22 for separation and further treatment within the process in the manner heretofore set forth. Thus, the 2,3-dimethylpentane will be recovered in the overhead fraction from fractionator 22, while the trimethylpentanes will be supplied in the bottoms fraction to demethylation treatment.

25 The overhead fraction from fractionator 134, which will comprise principally triptane, may be withdrawn therefrom through line 143, valve 144, condenser 145, rundown line 146 and valve 147 to receiver 148, having conventional gas release line 149 containing valve 150. The condensate from receiver 148 may be withdrawn therefrom through line 151 and valve 152 to pump 153, by means of which a regulated portion thereof may be recycled by way of line 154 containing valve

30 155 to the upper portion of fractionator 134 to serve as a cooling and refluxing medium therein, while the remaining portion of the triptane product may be withdrawn through line 156 and valve 157 and recovered as a final product of the process.

40 In accordance with a preferred embodiment of the present invention, the methane fraction being supplied through line 104 may be subjected to suitable treatment for conversion thereof into hydrogen. One suitable process comprises the

45 so-called water-gas reaction in which the methane fraction is treated with water in the form of steam at elevated temperatures in the presence of suitable catalysts to form hydrogen. This process is well known and no novelty is claimed herein for the process per se. A number of suitable catalysts may be employed; nickel, iron and cobalt being among the more common catalysts used.

The temperature employed will vary with the particular catalyst and other conditions of operation and in some cases it may be as low as 600° F. while in other cases may be as high as 1800° F. It is understood that the present invention is not limited to any particular catalyst or temperature employed in this step of the process since the only requirement, insofar as the combination aspect of the present invention is concerned, is that at least a portion of the methane be converted into hydrogen. In this process, carbon dioxide and some carbon monoxide is

55 usually produced and it is preferred to utilize a suitable solvent or other means for separating the carbon oxides from the hydrogen in order to leave a substantially pure hydrogen product.

Another method of converting the methane into hydrogen within the scope of the present invention is by cracking the methane either in the presence or absence of suitable catalysts. In this method of operation the temperature employed is usually within the range of from about 1200° to 70 about 1800° F. When employed, any suitable

catalyst may be used and here again a large variety of catalysts have been proposed for effecting the decomposition of methane into hydrogen.

Referring again to the drawing, the methane fraction being supplied through line 104 may be directed into heating coil 158 disposed in furnace 159. In case the water-gas reaction is employed, steam may be introduced through line 160 and valve 161 to commingle with the methane fraction in line 104 and then directed into heating coil 158. If the methane conversion step comprises the cracking of the methane, line 160 may be omitted or it may be utilized for the introduction of additional methane from an extraneous source or for any other desired purpose. The heated products from coil 158 may be directed through line 162 and valve 163 into reactor 164. The catalyst, when employed, may be disposed within reactor 164 and the heated hydrocarbons suitably contacted therein. Either up or downflow may be employed, as desired. The exact form of reactor 164 will depend upon the particular process being employed.

The products from reactor 164 may be directed through line 165 and valve 166 to separator and purifier 167. The design of zone 167 will depend upon the particular process utilized for converting the methane into hydrogen. For example, in case this process comprises the water-gas reaction, zone 167 preferably consists of one or more fractionating zones in which the products are treated with a suitable solvent or other means in order to separate the hydrogen from other products. Unconverted methane may be withdrawn from the lower portion of zone 167 through line 168 and may be removed from the process through valve 169 or all or a portion thereof may be recycled by way of line 170, valve 171 and line 104 to heating coil 158 for further conversion therein.

The hydrogen separated in zone 167 may be withdrawn therefrom through line 172 and may be directed through line 172' and valve 173 into line 47 to be supplied to the demethylation step of the process in the manner heretofore set forth. Usually the hydrogen recovered from zone 167 will be saturated with moisture at the temperature conditions at which it is recovered. As heretofore stated, moisture is detrimental to the demethylation catalyst and, in the preferred embodiment of the present invention, the hydrogen fraction is directed from line 172 through line 174 and valve 175 into dryer 176. It is also within the preferred embodiment of the invention that, when the hydrogen introduced to the process from an extraneous source contains moisture, the hydrogen be introduced to the process through line 177 and valve 178, instead of through line 47 and valve 48 as heretofore set forth. Dryer 176 may comprise any suitable apparatus and contain any suitable absorbent material, such as alumina or the like, in order to reduce the water content of the hydrogen fraction to as low as practicably possible and preferably to completely remove the water. Either upflow or downflow may be employed in dryer 176, as desired, and the dried hydrogen fraction may then be directed through line 179 and valve 180 into lines 172, 172' and 47 to be supplied to the demethylation step of the process as heretofore set forth.

It is a particular feature of the combination aspects of the present invention that at least sufficient hydrogen will be produced in the methane conversion step of the process to meet the requirements of the demethylation reaction. When the methane conversion step comprises a

water-gas reaction, three molecules of hydrogen are theoretically obtainable from one molecule of methane and one molecule of steam, or four molecules of hydrogen are theoretically obtainable from one molecule of methane and two molecules of steam, depending upon whether carbon monoxide or carbon dioxide is formed. Likewise, in the cracking of methane, two molecules of hydrogen are theoretically possible from one molecule of methane. Since the methane conversion step will convert at least 50% and usually a much higher proportion of the methane into hydrogen, it is readily seen that sufficient hydrogen to meet the requirements of the demethylation process will be available, thus providing a unitary process. Any excess hydrogen may be withdrawn from the system through an extension of line 172 and valve 173.

The following example is introduced to further illustrate the novelty and utility of the present invention but not with the intention of unduly limiting the same.

The charging stock to the process may comprise 65.4 moles per day (equivalent to 1257 gallons per day) of an isoctane fraction as heretofore described and is supplied at a temperature of 100° F. to fractionator 3 which may be operated with a top temperature of 215° F. and a bottom temperature of 245° F. A bottoms fraction comprising 13 moles per day (equivalent to 251 gallons per day) of higher boiling bottoms is withdrawn and recovered, while an overhead fraction comprising 52.4 moles per day (equivalent to 1006 gallons per day) is supplied to fractionator 22 which may be operated with a top temperature of 211° F. and a bottom temperature of 230° F. An overhead fraction comprising 34.7 moles per day (equivalent to 662 gallons per day) and comprising principally 2,2,4-trimethylpentane is recovered from fractionator 22. The bottoms product from fractionator 22 comprises 30.4 moles per day (equivalent to 573 gallons per day). A hydrogen fraction containing 91.2 moles per day of hydrogen and 9.1 moles per day of methane, to make a total of 100.3 moles per day of gas, is heated to a temperature of about 500° F. at a pressure of about 500 pounds per square inch. The bottoms fraction from fractionator 22 is likewise heated to a temperature of 500° F. at a pressure of about 500 pounds and the heated products are supplied to reactor 61 containing a hydrogenating catalyst comprising 66 per cent by weight of total nickel, 30 per cent of diatomaceous earth and 4 per cent of oxygen as nickel oxide.

Reactor 61 may comprise an insulated reaction chamber having catalysts containing tubes disposed therein and communicating with drum 62 containing Dowtherm. The Dowtherm is maintained at a pressure of 12 pounds absolute at the top and 14 pounds absolute at the bottom, and the circulation rate is controlled so that the temperature of the heat exchange medium in the lower portion of the space surrounding the tubes in reactor 61 is about 490° F. and the temperature in the upper portion of this space is about 480° F.

The demethylation products are withdrawn from reactor 61 at a temperature of about 495° F., cooled in condenser 88 to a temperature of 90° F., and then supplied to flash zone 91 at a pressure of about 200 pounds per square inch. A fraction rich in hydrogen is withdrawn from the upper portion of zone 91 and is recycled to the demethylation process, while the liquid products are flashed in a second flash zone at a pressure

11

of about 70 pounds and then flashed in a third flash zone at a pressure of about 25 pounds per square inch. The overhead products from the second and third flash zones are supplied to treatment in the methane conversion step of the process.

The bottoms product from the last flash zone is supplied to fractionator 112 which may be operated with a top temperature of 130° F. and a bottom temperature of 185° F. An overhead product comprising principally 2,2- and 2,3-dimethylbutane is separated and recovered as one of the final products of the process. The bottoms product from fractionator 112 is supplied to fractionator 134 which may be operated with a top temperature of 185° F. and a bottom temperature of 200° F. An overhead fraction comprising triptane is separated and recovered as a final product of the process, while the bottoms product from fractionator 134 may be recycled to fractionator 22 for further separation and treatment within the process.

In a process such as hereinbefore described, there may be produced, based upon an isoctane fraction charge of 1257 gallons per day, the following products:

	Gallons per day
Higher boiling isoctane bottoms	251
2,2,4-trimethylpentane and 2,3-dimethylpentane fraction	662
2,2 and 2,3-dimethylbutane fraction	77
Triptane fraction	193
	1183

The triptane fraction will be of high purity and will be particularly suitable for blending in aviation gasoline or may be used for any other desired purpose.

The previously separated methane fractions are reacted with steam in the presence of a nickel catalyst promoted with alumina at a temperature of about 1300° F. to produce carbon monoxide and hydrogen. The products may then be reacted with additional steam at about 900° F. in the presence of an iron oxide catalyst promoted with chromium oxide to form carbon dioxide and hydrogen. The carbon dioxide may be separated from the hydrogen by absorption in a solvent comprising ethanol amine, and the hydrogen may then be supplied to the demethylation process in the manner hereinbefore described.

We claim as our invention:

1. A process for the production of triptane from an isoctane fraction comprising 2,2,4-, 2,2,3-, 2,3,4- and 2,3,3-trimethylpentanes and higher boiling compounds, which comprises fractionating said isoctane fraction to separate higher boiling compounds from the trimethylpentanes, further fractionating the trimethylpentanes to separate 2,2,4-trimethylpentane from a fraction comprising the other trimethylpentanes, heating the last men-

12

tioned fraction to a selective demethylation temperature, simultaneously heating a hydrogen fraction to substantially the same temperature, commingling the heated fractions and contacting the same with a nickel catalyst at a temperature of the order of 500° F. and at a superatmospheric pressure of the order of 500 pounds per square inch, flashing and reducing the pressure of the products of said demethylation to a pressure of the order of 200 pounds per square inch to separate a hydrogen fraction, recycling the hydrogen fraction to said demethylation, further reducing the pressure of said products to a pressure of the order of 70 pounds per square inch to separate a methane fraction, fractionating the remaining products to separate an overhead fraction containing 2,2- and 2,3-dimethylbutanes from higher boiling products, further fractionating the higher boiling products to separate a triptane fraction from higher boiling trimethylpentanes.

2. The process of claim 1 further characterized in that at least a portion of the last mentioned higher boiling trimethylpentanes is recycled to further selective demethylation treatment.

3. The process of claim 1 further characterized in that the amount of hydrogen is of the order of 3 moles of hydrogen per mole of said other trimethylpentanes.
